The ornamental design for a necklace, as shown and described.

DESCRIPTION

FIG. 1 is a front elevation view of the necklace showing my design;

FIG. 2 is a back elevation view thereof;

FIG. 3 is a side elevation view thereof;

FIG. 4 is an opposite side elevation view thereof;

FIG. 5 is a top plan view thereof;

FIG. 6 is a bottom plan view thereof;

FIG. 7 is an upper perspective view thereof; and,

FIG. 8 is an enlarged partial perspective view of a pendant portion of the necklace.

The evenly-spaced dashed broken lines in the figures depict portions of the necklace that form no part of the claimed design. The unevenly-spaced dot-dash broken lines in the figures define boundaries of the claimed design and form no part of the claimed design. The appearance of any portion of the article between the pairs of dot-dash broken lines forms no part of the claimed design.
